UNITED STATES PATENT OFFICE.

FRANK GEIGER, OF IMPERIAL JUNCTION, CALIFORNIA.

SUPPORTING AND DELIVERING DEVICE.

1,088,979.

Specification of Letters Patent.

Patented Mar. 3, 1914.

Application filed August 11, 1913. Serial No. 784,137.

To all whom it may concern:

Be it known that I, FRANK GEIGER, a citizen of the United States, residing at Imperial Junction, in the county of Imperial and State of California, have invented certain new and useful Improvements in Supporting and Delivering Devices, of which the following is a specification, reference being had to the accompanying drawings.

10 This invention relates to supporting and delivering devices, and it more particularly relates to a device of this character which is designed for supporting and delivering train orders, messages, etc., to the conductor or other occupant of moving trains.

One of the objects of this invention is to provide a device of this character which will support the message or article to be delivered in the most convenient position to be 20 caught by the moving train or by an occupant thereof, so that detriment to the article delivered and to the person to whom it is delivered is effectually avoided.

Another object of the invention is to provide a device of this character on which several articles may be supported for delivery to different trains or to different persons in the same train.

Another object is to provide practical and 30 effective means for displaying the articles to be delivered at night, and for indicating the specific article which is to be delivered to a certain train.

Another object is to provide a device of 35 this character which is simple of construction, comparatively inexpensive, strong, and durable, easy of access, easy to manipulate, and thoroughly practical and effective.

In the accompanying drawings, which 40 supplement this specification, Figure 1 is an elevation view of the device in its operative position; Fig. 2 is an enlarged horizontal sectional view through the standard 14, illustrating the base in plan; Fig. 3 is an 45 enlarged fragmental vertical sectional view through one of the blocks 11 and brackets 12 and their adjuncts; Fig. 4 is an enlarged fragmental elevation view of the bar and the brackets which support the lantern-basket; Fig. 5 is an enlarged vertical sectional view 50 through the lantern-basket and its adjuncts; Fig. 6 is a top plan view of one of the brackets 12 and its adjuncts, the standard 14 being shown in section; Fig. 7 is 55 a vertical sectional view through the brackets 12 and certain of their adjuncts; Fig. 8

is a horizontal sectional view through the standard 14, brackets 12 and a portion of one of the blocks 11; Fig. 9 is a plan view of the bracket which supports the lantern-basket; Fig. 10 is an enlarged detail view partly in section, of the standard 14 and the spring element 12 and their adjuncts; Fig. 11 is an enlarged elevation view of one of the blocks 11; Fig. 12 is an enlarged end elevation view of one of said blocks 11; Fig. 13 is a fragmental detail view, partly in horizontal section; Fig. 14 is a side elevation view of one of the blocks 11; and Fig. 15 is an enlarged vertical sectional view through the bracket 12 and certain of its adjuncts.

In these drawings, in which similar reference characters correspond with similar parts throughout the several views, the device which constitutes my invention is especially adapted for supporting a hoop or loop 10, of known construction, which is adapted to securely engage a package, message or train order, and is provided with a horizontally extending arm or shank 10', the latter being adapted to be snugly and removably seated in an aperture 11' of a block 11, said block also being provided with an aperture 11^a which extends vertically therethrough. This block is provided 80 with a convexed or semi-cylindrical end 11^b, and is seated between the substantially parallel arms of a U-shaped bracket 12, provided with an aperture 12' through its bight portion, and with opposite apertures 12^a 90 through its end portions. These apertures 12^a register with the aperture 11^a of the block 11, and a vertically disposed pivot 13 extends through these registering apertures and secures the block 11 in pivotal relation 95 with the bracket 12, the latter being secured to a vertical standard 14 by means of a bolt 15 which extends through the aperture 12' and through a registering aperture in the standard 14.

A substantially U-shaped spring member 16 is provided with an aperture 16' in its bight portion and with opposite apertures 16^a in its substantially parallel side portions 16^b, the ends of said spring being 105 gradually curved outward at 16^c. A bolt 17 extends through the apertures 16^a, and a spring 18 is seated between the head of the bolt and one of the spring elements 16^b, while a similar spring 18 is seated between 110 the other element 16^b and a nut 17' which is threaded on the bolt 17. The spring mem-

ber 16 is seated between the spaced sides of the bracket 12, while the aperture 16' registers with the aperture 12', so that the bolt 15 serves to secure the members 12, 14 and 16 rigidly together. The semi-cylindrical end 11^b of the block 11 extends between the curved ends 16^c of the spring member 16, and this block is normally held in the longitudinal plane of the members 12 and 16 by 10 the tension of said spring member, and this tension is adapted to be increased or decreased, to suit the attending wind and weather conditions, by adjusting the nut 17' on the bolt 17.

15 An arm 19 is secured on the block 11 and extends therefrom in the longitudinal direction thereof, and this arm has its free end bifurcated or provided with a V-shaped notch 19' which is adapted for engagement with the loop 10 for holding it in a vertical plane. A spring 20, which is preferably in the form of a wire loop, is secured on the block 11 and extends outward therefrom over the aperture 11' being curved downward in its 25 medial portion, and upward at its end, so as to frictionally engage with the shank 10' and prevent accidental displacement thereof.

30 While the foregoing description has been confined principally to one of the package-holding mechanisms, it is obvious that any desired number of these mechanisms may be employed, either by extending the height of the staff or standard 14 or by increasing or decreasing the distance between said mechanisms. However, as illustrated, the device 35 includes three of these mechanisms supported on the staff 14, said staff being pivotally mounted in a bracket, base or stand 21 which may be secured to a wooden or concrete sub-base 22. The base 21 is provided with a socket 21' and with a bearing aperture 21^a, in which the staff 14 is seated, a collar 23 being provided on the staff 14 immediately below the bearing 21^a for preventing upward movement of the staff. Secured 40 on the staff 14 immediately above the bearing 21^a is an arm 24 which has a pivotally mounted extension 25, the latter constituting a handle and a locking element, whereby 45 the staff 14 may be turned through an angle of approximately 90 degrees, and locked in or out of operative position by engagement with either of two pairs of spaced lugs 26. One of the three legs of the base member 21 50 is formed with steps 21^b, on which an attendant may mount for manipulating the device and the packages supported thereby.

55 Pivottally mounted on the upper and lower pivot members 13 is a lantern support or bracket 27, preferably formed from a bar or rod which is rectangular in cross section and having its medial portion 27' in vertical position adjacent to the free ends of the arms 19, while the upper end portion 27^a is 60 in horizontal position and pivotally con-

nected to the upper bracket 12 by means of the bolt 13; the lower element 27^b of the member 27 being pivotally connected to the lower bracket 12 by means of its pivot element 13; this lower element depending from 70 said bracket 12 and from the element 27' a considerable distance below the lower arm 19. Upon this bracket 27 is slidably mounted a basket or lantern receiver 28, a spring 29 being carried by the basket in frictional engagement with the bracket 27. It will be seen that this basket may be slid up and down on the bracket 27, so as to be located contiguous to whichever of the package supporting mechanisms is to be next displayed and delivered. The lower free end of the bracket 27 is bifurcated, or V-shaped, and an apertured slide block or stop member 30 is adapted to be secured interchangeably to the furcations or arms 27' and to rest 80 against the lower bracket 12. By this means, it will be seen that the bracket 27 is supported in a different plane from the plane of the package supporting mechanisms, and is out of the way thereof, while 90 supporting a lantern in such position as to illuminate and display the article to be delivered, and to indicate the position thereof; so that the person who is to catch the loop 10 may be properly positioned for doing so 95 before the train reaches the package or message supporting device.

From the foregoing it will be seen that I have provided a device of this character which is fully capable of attaining the foregoing objects in a thoroughly practical and effective manner.

100 While the accompanying drawings illustrate what I believe to be the preferred embodiment of my invention, it is to be understood that the invention is not limited thereto, but that various changes may be made in the construction, arrangement and proportions of the parts without departing from the scope of the invention, as defined 105 in the appended claims.

I claim:

1. In combination, a device adapted to hold a package and provided with a substantially horizontal shank; a block having 115 a substantially horizontal aperture in which the shank is movably seated, said block having a spring element adjacent to the aperture and frictionally engaging the shank, a standard, a substantially U-shaped bracket 120 on the standard, a substantially U-shaped spring between the arms of the U-shaped bracket, and a pivot element extending through said bracket and said block and securing the latter with one end between the 125 arms of the substantially U-shaped spring.

2. The combination with an article supporting device including a substantially horizontal shank, of an elongated block 130 formed with a longitudinal aperture in one

end and having its other end convexed and having a vertical aperture in its medial portion, an arm extending from the block in the longitudinal direction thereof and engaged 5 with the article supporting device, a bracket, a pivot extending through the vertical aperture of the block and connecting it to the bracket, and a spring connected to the bracket and engaging with the convexed 10 end of the block.

3. The combination with an article supporting device including a shank, of an elongated and pivotally mounted block provided with a longitudinal aperture and with 15 a longitudinal arm extending outward past the aperture and adapted for engagement with said article supporting device, a spring carried by said block in frictional engagement with said shank, and a spring engaged 20 with said block for holding it in its normal position and allowing it to be swung horizontally.

4. In combination, a base, a standard supported by the base, several article delivering mechanisms carried by the standard, a bracket pivotally connected to certain of 25

said mechanisms and provided with a substantially vertical element, and a lantern receiver carried by the vertical element and being adjustable thereon and adapted to be 30 located adjacent to either of the supporting mechanisms.

5. In combination, a base, a standard supported on the base, several article delivering mechanisms carried by the standard, a 35 bracket pivotally connected to certain of said mechanisms and provided with a substantially vertical element, and a lantern receiver carried by the vertical element and being adjustable thereon and adapted 40 to be located adjacent to either of the several article supporting mechanisms, said bracket being provided with means for holding it in either of two vertical planes which are spaced apart from the plane of the article 45 supporting mechanisms.

In testimony whereof I hereunto affix my signature in the presence of two witnesses.

FRANK GEIGER.
